UNITED STATES PATENT OFFICE

TAIN G. McDUGAL, OF FLINT, MICHIGAN, ASSIGNOR TO A C SPARK PLUG COMPANY, OF FLINT, MICHIGAN, A COMPANY OF MICHIGAN

SPARK PLUG

Application filed May 28, 1928. Serial No. 281,205.

This invention relates to spark plugs for internal combustion engines, and more particularly to an improvement in the method of assembly and the structure of the center electrode in an insulator core of quartz.

The use of fused silica or moulded quartz as a spark plug insulator core is highly desirable, principally because it is one of the best known non-conductors of electricity at all temperatures, coupled with the fact that it may be heated rapidly or subjected to sudden changes in temperature without liability of fracture or cracking.

The most remarkable property of quartz is its low factor of expansion. Quartz has practically no expansion. Since quartz does not expand except to an infinitesimal extent and, whereas the usual metal electrode of a spark plug has a relatively high factor of expansion, considerable trouble has been experienced heretofore in assembling these two different materials, to effect and maintain a tight seal so as to avoid leakage of compressed gases.

The present invention contemplates the provision of an improved type of spark plug unit, comprising a moulded insulator core of fused quartz, in which is embedded or formed in situ therein, a portion of a conductor or electrode in a manner to overcome the difficulties encountered in the past with plugs having insulator cores of quartz.

The invention will be more fully comprehended upon reference to the accompanying drawing in which:

Figure 1 is a vertical sectional view of a spark plug embodying the invention;

Figure 2 is a transverse sectional view on line 2—2 of Figure 1;

Figure 3 is a vertical sectional view of a spark plug showing a modification; and

Figure 4 is a transverse section taken on line 4—4 of Figure 3.

In the drawing, the reference character 1 indicates an outer metallic shell having a screw threaded portion for engagement within an opening in the engine cylinder and which surrounds an insulator core 2 of fused quartz or similar material, enclosing the center electrode comprising a tip portion 3, an

intermediate flexible portion 4 of a size smaller than the diameter of the central bore in the insulator core 2, and a screw-threaded terminal portion 5 projecting beyond the top of the core 2, for the attachment of a binding nut to connect the electrode with a current-conducting wire leading from an ignition distributor or similar device.

The method of producing the insulator and electrode unit may consist in moulding the fused quartz directly about a portion of the electrode tip 3, which is preferably of conical shape, to insure a firm embedment, and then inserting the flexible portion 4 through the central bore of the core and electrically welding the lower end thereof to the conical tip 3. Because of the low coefficient of expansion of the quartz, the shrinkage of the core upon cooling would not be sufficient to break the tight seal between adjacent portions of the core and electrode tip. Neither will the seal be broken by the tendency of the tip to expand and contract upon temperature changes, since the extent of contact of the parts is so small as not to be affected by the total linear expansion. The linear expansion of the electrode portions 4 and 5 relative to the core is compensated for by the flexibility of the portion 4, which allows this intermediate electrode portion to bend to accommodate the extension, and so prevents the imposition of strains upon the parts.

If desired, the electrode tip 3 and portion 4 may be united prior to the step of moulding the core and, in such event, the flexible intermediate portion is preferably coated with some suitable material, such as graphite, which will pass away or oxidize from the heat of the moulding operation or from heat subsequently applied, and so afford clearance for the flexing of the portion 4.

The same sort of coating would be applied to the upper portion of the continuous or one-piece center electrode 7 shown in the modified construction of Figure 3. The moulding of the core 8 would then result in a tight seal or union at the bottom of the core with the uncoated portion of the electrode and, upon the subsequent removal of the graphite coating, clearance space would be provided.

for the flexing of the conductor as before referred to.

I claim:

1. The process of making a spark plug unit consisting of coating a portion of an electrode with graphite or the like, and then molding fused quartz or similar insulation around the electrode so as to embed the uncoated portion directly therein and subsequently removing the graphite coating to provide clearance space between adjacent portions of the electrode and insulation.

2. The process described in claim 1, wherein the removal of the graphite coating consists of the oxidation of the graphite.

3. The process of making a spark plug unit consisting in molding fused quartz or the like about an electrode a portion of which is coated with graphite or its equivalent to directly embed the uncovered portion of the electrode therein.

4. The process of making a spark plug unit consisting of coating a flexible electrode for a portion of its length with graphite, then molding about the electrode a fused quartz core, whereby the uncoated electrode portion is directly embedded in the core and subsequently burning the graphite to provide clearance space in the core in which the unembedded electrode portion is free to flex.

5. The process of making a spark plug unit consisting in molding fused quartz or the like about a central core comprising an exposed metallic electrode portion and a graphite portion to directly embed the exposed portion therein.

6. The process of making a spark plug unit consisting in molding fused quartz or the like about a central core comprising an exposed metallic electrode portion and a graphite portion to directly embed the exposed portion therein, and then removing the graphite portion of the core.

7. The process of making a spark plug unit consisting in molding fused quartz or the like about a central core comprising an exposed metallic electrode portion and a graphite portion to directly embed the exposed portion therein, then removing the graphite portion of the core and inserting in the space from which the graphite portion has been removed a second electrode portion and securing the same in electric connection relation to the embedded electrode portion.

8. The process of making a spark plug unit consisting of molding fused quartz or the like about a conductor portion to constitute an insulator, inserting a second conductor portion in the bore formed in the insulator, said second conductor portion being flexible and of smaller diameter than the bore of the insulator, and then molecularly uniting said conductor portions with each other.

9. The process of making a spark plug unit consisting of molding an insulator core of

quartz or the like with an electrode tip embedded in the lower end thereof, inserting a flexible conductor through the bore of the insulator into contact with said tip and then welding the conductor to said tip.

In testimony whereof I affix my signature.
